[57] CLAIM

The ornamental design for an escutcheon for a key operated gas valve, as shown and described.

DESCRIPTION

FIG. 1 is a top perspective view of an escutcheon for a key operated gas valve showing my new design;

FIG. 2 is a bottom perspective view thereof;

FIG. 3 is a top plan view thereof;

FIG. 4 is a bottom view thereof;

FIG. 5 is a side elevational view thereof;

FIG. 6 is a sectional view taken along line 6—6 of FIG. 3; and,

FIG. 7 is a side elevational view showing a gas valve and operating key therefore in broken lines illustrating environmental structure.
